UNITED STATES PATENT OFFICE.

ELI BROTHERS, OF LYNN, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON SHOES.

1,146,304.

Specification of Letters Patent. Patented July 13, 1915.

Application filed July 8, 1911. Serial No. 637,413.

To all whom it may concern:

Be it known that I, ELI BROTHERS, a citizen of the United States, residing at Lynn, in the county of Essex and State of Massachusetts, have invented certain new and useful Improvements in Machines for Operating on Shoes; and I do hereby declare the following to be a full, clear, and exact description of the invention, such as will 5 enable others skilled in the art to which it appertains to make and use the same.

The present invention relates to machines for operating upon shoes in which the point of operation of the operating mechanism is transferred around the shoe. In the operation of machines of this class the shoe is usually supported in the hand of the operator and is manipulated by him to properly present the different portions thereof 15 to the mechanism for operating thereon. The movements which are imparted to the shoe by the operator during the operation of the machine thereon consist of lateral turning movements to bring the margin of the sole adjacent the point of operation into 20 a position substantially parallel with the line of feed, and lateral and longitudinal tipping or tilting movements to bring the portion of the shoe in proximity to the operating mechanism into the desired plane. Machines have been devised in which the shoe is supported upon a movable jack and relative movements are automatically imparted to the operating mechanism and the 25 jack to bring the shoe into proper relation to the operating mechanism. These machines are complicated in construction and expensive to manufacture.

The primary object of the present invention is to produce an improved and simplified machine for operating on shoes by which the shoe is supported and automatically manipulated to properly present the various portions thereof to the operating 40 mechanism as the point of operating of said mechanism is transferred around the shoe.

In carrying out the above object, one feature of the invention contemplates the provision in a machine of the class referred to of a shoe supporting jack, a track secured to said jack, and guides engaging said track and co-operating therewith to impart tipping and lateral turning movements to the jack.

Other features of the invention consist in 55 certain constructions, arrangements and

combinations of parts, the advantages of which will be obvious to one skilled in the art from the following description.

In the drawings illustrating the invention in the best form at present known to the 60 inventor;—Figure 1 is a side elevation of a portion of a shoe sewing machine embodying the invention illustrating a shoe in position on the shoe supporting jack; Fig. 2 is a detail front elevation of the shoe 65 supporting jack, the track secured to the jack and the table supporting the jack; Fig. 3 is a plan view of a portion of the mechanism shown in Fig. 2; Fig. 4 is a front elevation of the guides for engaging the 70 track and the mechanism supporting the guides, showing certain parts thereof in position to permit the insertion of the track; Fig. 5 is a sectional view taken on the line 5—5 of Fig. 4, showing the parts 75 in operative position.

The present invention as illustrated in the drawings has been embodied in a Goodyear welt and turn shoe sewing machine of the type disclosed in the patent to French & 80 Meyer, 413,704. Only so much of the sewing mechanism as is necessary for a clear understanding of the invention has been shown in the drawing. The curved hook needle is indicated at 1, the feed point at 85 2 and the channel guide at 3, all of these parts being constructed, arranged and operated as shown and described in the French & Meyer patent. As is well known to those skilled in the art, in sewing machines of 90 this type, the feed point is brought forward at intervals to engage the shoe and is moved laterally together with the channel guide to impart feeding movements to the shoe, thereby transferring the point of operation of the stitch forming mechanism about the shoe.

The lasted shoe is supported by a jack adapted to hold ordinary wooden lasts, upon which welt and turn shoes are lasted. This 100 jack is indicated as a whole at 4 and is provided with the usual last pin 5 carried by the block 6 pivoted at 7 upon a segmental block 8 and held in position with relation to said block by a pawl 9 which is arranged to engage teeth 10 formed on said block. The segmental block 8 is arranged for adjustment on the supporting plate 11 of the jack frame to accommodate lasts of different sizes by providing the plate 11 with a slot 110

11^a and securing the block 8 to the plate by a clamping screw, 8^a passing through the slot and screwed into the block. A toe support 12 is carried by a supporting bolt 13 mounted in an arm 14 of the jack frame. In order to provide for the transverse adjustment of the support, said support is formed with a transverse groove 15 shaped to receive the head of the supporting bolt 13, and the support is clamped in adjusted position on said bolt by a nut 16. The bolt 13 is received in perforations in spaced portions of the arm 14, and the toe support is adjusted for lasts of different sizes by means of the nut 17 threaded on said bolt and interposed between the spaced portions of the arm. The jack is mounted upon a standard 18 and is supported to maintain the shoe in position to be engaged by the feed point and the channel guide by means of a table 19 mounted on a rod 20 arranged to slide vertically in a bracket 21 and pressed upwardly by a lever 22 operated by a counterbalance weight 23. By this means the shoe is also maintained in engagement with the feed point and channel guide during the feed movements thereof. In order to permit the jack to tip laterally and longitudinally to bring a portion of the shoe at the point of operation of the sewing mechanism into the proper plane, the jack is connected to the standard 18 by any suitable form of universal joint indicated at 24. The standard 18 is provided with antifriction rolls 25 so that the standard moves freely over the surface of the table during the movements imparted to the jack in the sewing operation. The mechanism for actuating the jack to bring the shoe into proper relation to the sewing mechanism as the point of operation of said mechanism is transferred around the shoe comprises a track indicated at 26 and shown in detail in Figs. 2 and 3. This track in the present embodiment of the invention consists of a sheet metal annulus bent in a shape corresponding approximately with the outline of the sole of a shoe and formed with parallel edges curved to correspond approximately with the curvature of the marginal portion of the face of the sole. The track therefore forms a pattern curved to correspond approximately to the curvature of the marginal portion of a shoe sole. The inner and outer faces of the track are formed so that the elements of these surfaces vary in angular position in different portions of the track. In the construction illustrated the angular position of the elements of the lateral surfaces at the toe portion is varied from that at other portions thereof, as is clearly shown in Fig. 1. A series of guides are arranged to engage this track and operate therewith to move the jack to properly present the shoe to the stitch forming mechanism as the shoe is fed. In the pres-

ent embodiment of the invention these guides consist of a plurality of guide rolls engaging the upper and lower edges and the inner and outer faces of the track. A pair of these guide rolls engaging the upper edge of the track are indicated at 27. These rolls are mounted on an arm 28 of a member 29 carried by guide rods 30 and 31 arranged to slide in sleeves 32 and 33 formed on a hanger 34 pivotally supported by a shaft 35 carried by spaced arms 36 and 37 supported by slides 38 and 39. Coiled springs 40 and 41 surrounding the guide rods 30 and 31 are interposed between the sleeves 32 and 33 and the member 29 to resiliently support the said member. A second pair of guide rolls 42 are carried by the member 29 and are arranged to engage the lower edge of the track in opposed relation to the rolls 27. In order to prevent binding of the track between the guides due to the curvature of the track, the rolls 42 are mounted upon pins 43 arranged to slide in guides 44 in the member 29 and are resiliently held against the lower edge of the track by coil springs 45. A third pair of guide rolls 46 arranged to engage the outer face of the track are mounted in the member 29 upon pins 47 arranged to move in guides 48 in the member 29 and are resiliently held in engagement with the track by coil springs 49. Guide rolls 50 are arranged to engage the inner face of the track in opposed relation to the rolls 46. In order to permit the removal of the track from between the guide rolls and the substitution of another of different shape or size, the rolls 50 are mounted upon a swing frame 51 arranged to swing on a shaft 52 carried by the member 29 so that the frame 51 may be swung downwardly into the position shown in Fig. 4. When the track is inserted in position between the guide rolls, the swing frame 51 is swung upwardly to bring the rolls 50 into engagement with the inner face of the track and is then locked in position by a screw pin 52^a which is passed through a perforation in the swing frame 51 and through a registering perforation in an arm 53 formed on the member 29.

In order to provide for angular adjustment of the guides to vary the angular position of the jack, the hanger 34 is provided with a segment 54 in which are formed a series of perforations 55. A projection 56 on the arm 37 extends downwardly in front of the segment 54 and is provided with a slot 57 with which any one of the perforations in the segment 54 may be brought into registration by turning the hanger 34 on the shaft 35. The hanger and the parts connected therewith are held in adjusted position on said shaft by a pin 58 passed through the slot and engaging one of said perforations.

The slide 38 which coöperates with the slide 39 in supporting the guide mechanism is constructed, arranged and operated in the same manner as the back gage of the 5 sewing machine of the French & Meyer patent referred to above. The guides are therefore free to move transversely of the vertical plane of the line of feed during the feed movement of the shoe thereby permitting the shoe to assume the desired position 10 with relation to the sewing mechanism, and are locked in position during the operation of the stitch forming mechanism to firmly support the jack and shoe against 15 the action of said mechanism.

In the operation of sewing a shoe, the lasted shoe is first placed in position on the jack with the channel guide of the sewing mechanism engaging the channel of the shoe 20 in the well known manner, the shoe being held in engagement with the channel guide by the jack supporting table 19. When the sewing mechanism is in operation, feed movements are imparted at intervals to the 25 shoe by the lateral movement of the feed point 2 thereby moving the jack upon which the shoe is supported at intervals in the direction of the line of feed, and during these movements of the jack, the track 26 moves 30 forwardly through the guide rolls of the guide mechanism. By the engagement of the guides with the curved lateral faces of the track, lateral turning movements are imparted to the jack to place the margin of 35 the sole adjacent the sewing mechanism in a position substantially parallel with the line of feed. The engagement of the guides with the curved edges of the track during the movements thereof causes tipping movements to be imparted to the jack angularly 40 with respect to the line of feed. By reason of the formation of the lateral faces of the track so that the elements thereof vary in angular position, tipping movements are 45 imparted thereto about an axis substantially coincident with the line of feed. Inasmuch as these movements take place only during the feed movement of the shoe when the feed point is in engagement with the sole, 50 the lateral turning and longitudinal and lateral tipping movements which are imparted to the jack take place about the point of operation of the stitch forming mechanism.

55 Although the invention has been shown and described as embodied in a shoe sewing machine, certain features thereof may be embodied in other machines in which the point of operation of the operating mechanism is transferred about the shoe, such as pegging and nailing machines, lasting machines, sole edge trimming and finishing machines, etc.

Having explained the nature and object 60 of the invention and having specifically de-

scribed one form of mechanism in which it may be embodied, what is claimed is:—

1. A machine for operating on shoes having, in combination, mechanism for operating on the shoe, a shoe supporting jack, a track secured to said jack, and guides engaging the upper and lower edges and the inner and outer faces of said track and coöperating therewith to impart tipping and lateral turning movements to said jack as 70 the point of operation of the operating mechanism is transferred around the shoe to bring the shoe into proper position with relation to the operating mechanism, substantially as described. 75

2. A machine for operating on shoes having, in combination, mechanism for operating on the shoe, a shoe supporting jack, a track curved to correspond approximately with the curvature of the margin of the sole of a shoe, and guides engaging the upper and lower edges and the inner and outer faces of said track and coöperating therewith to impart tipping and lateral turning movements to said jack as the point of operation of the operating mechanism is transferred around the shoe to bring the shoe into proper position with relation to the operating mechanism, substantially as described. 80

3. A shoe sewing machine having, in combination, stitch forming mechanism, feeding means, a shoe supporting jack, a track secured to said jack and guides engaging the upper and lower edges and the inner and outer faces of said track and coöperating therewith to impart tipping and lateral turning movements to said jack as the point of operation of the stitch forming mechanism is transferred about the shoe to present the shoe properly to said mechanism, substantially as described. 95

4. A shoe sewing machine having, in combination, stitch forming mechanism, feeding means, a shoe supporting jack, a track secured to said jack, and guides engaging the upper and lower edges and the inner and outer faces of said track and coöperating therewith to impart tipping and lateral turning movements to said jack about the point of operation of the stitch forming mechanism as said point is transferred about the shoe to present the shoe properly to said mechanism, substantially as described. 100

5. A shoe sewing machine having, in combination, stitch forming mechanism, feeding means, a shoe supporting jack, a track secured to said jack, and guides engaging said track and arranged to move toward and from the vertical plane of the line of feed during the feed movement of the shoe, substantially as described. 110

6. A shoe sewing machine having, in combination, stitch forming mechanism, feeding means, a shoe supporting jack, a track secured to said jack, guides engaging said 115

track and arranged to move toward and from the vertical plane of the line of feed during the feed movement of the shoe, and means to lock said guides in position during the operation of the stitch forming mechanism, substantially as described.

7. A machine for operating on shoes comprising a shoe supporting jack, a track secured to said jack, guides engaging said track and coöperating therewith to impart tipping and lateral turning movements to said jack, and means to adjust the said guides angularly to vary the angular position of said jack, substantially as described.

10 8. A machine for operating on shoes comprising a shoe supporting jack, an annular track curved to correspond approximately with the curvature of the margin of the sole of the shoe secured to said jack, the elements 20 of the lateral faces of said track being varied in angular position in different portions of the track, and guides engaging said track and coöperating therewith to impart tipping and turning movements to said jack, 25 substantially as described.

9. A machine for operating on shoes having, in combination, mechanism for operating on the shoe, automatic shoe feeding means, a shoe supporting jack actuated by 30 said means, a track secured to said jack, guides engaging the upper and lower edges and the inner and outer faces of said track and coöperating therewith to impart tipping and lateral turning movements to said jack during the actuation of the jack by said means to bring the shoe into proper position with relation to the operating mechanism, 35 substantially as described.

10 10. A machine for operating on shoes comprising mechanism for operating on the shoe, automatic shoe feeding means, a shoe supporting jack actuated by said means, an annular track bent in a shape corresponding approximately with the contour of 45 the sole of a shoe secured to said jack, said track being formed with parallel edges curved to conform approximately with the curvature of the marginal portion of the face of the sole, guides engaging the inner and outer faces and upper and lower edges of said track and coöperating therewith to impart tipping and lateral turning movements to said jack during the actuation of the jack by said means to bring the shoe into 50 proper position with relation to the operating mechanism, substantially as described.

11. A machine for operating on shoes having, in combination, operating means, feeding means and shoe supporting means comprising a shoe supporting jack, a standard attached to said jack, a universal connection between said standard and said jack, a table supporting said standard, on which said standard is free to slide laterally, and yield-

ing means acting on said table to support 65 the same, substantially as described.

12. A machine for operating on shoes, having, in combination, devices for operating on the shoe, a shoe supporting jack, mechanism for imparting tipping and lateral turning movements to said jack as the point of operation is transferred about the shoe to bring the shoe into proper position with relation to the operating devices comprising a track secured to said jack, a slide, 75 guides secured to the forward end of said slide and engaging said track, and means for locking and unlocking said slide during each cycle of operations, substantially as described.

13. A machine for operating on shoes, having, in combination, devices for operating on the shoe, a shoe supporting jack, mechanism for imparting tipping and lateral turning movements to said jack as the point of operation of the operating devices is transferred about the shoe to bring the shoe into proper position with relation to said devices comprising a track secured to said jack, a slide arranged to move transversely of the vertical plane of the line of feed, and guides secured to the forward end of said slide and arranged to engage the upper and lower edges and the inner and outer faces of the track, substantially as described.

14. A shoe sewing machine, having, in combination, stitch forming devices including a curved hook needle, a track secured to the jack, guides engaging the upper and lower edges and the inner and outer faces of the track and coöperating with the jack to bring the shoe into proper relation to the needle as the sewing point is transferred about the shoe, substantially as described.

15. An inseam shoe sewing machine having, in combination, stitch forming mechanism including a curved hook needle, a channel guide, a shoe supporting jack, a track secured to said jack, guides engaging said track and coöperating therewith to impart tipping and lateral turning movements to said jack as the point of operation of the stitch forming mechanism is transferred around the shoe to bring the shoe into proper position for the passage of the needle through the between substance, substantially as described.

16. An inseam shoe sewing machine having, in combination, stitch forming mechanism including a curved hook needle, a channel guide, a shoe supporting jack, means for supporting the jack arranged to permit the jack to turn laterally and to tip in any direction, a track secured to said jack and guides engaging said track and coöperating therewith to impart tipping and lateral turning movements to said jack as the point

of operation of the stitch forming mechanism is transferred about the shoe to bring the shoe into proper position for the passage of the needle through the between substance.

5 17. A machine for operating on shoes having, in combination, mechanism for operating on the shoe, a shoe supporting jack, a track secured to said jack, and guides engaging said track and coöperating there-

with to impart automatic tipping and lateral 10 turning movements to said jack as the point of operation of the operating mechanism is transferred about the shoe, substantially as described.
